STIPPLING DEVICE

Charles W. Guimond, Grosse Pointe Woods, Mich.,
assignor to Drum Products Corporation, St.
Clair Shores, Mich., a corporation of Michigan

Application June 25, 1947, Serial No. 756,960

2 Claims. (Cl. 41—5.5)

1

This invention relates to devices for improving the appearance of painted surfaces and particularly to improvements in paint stipplers.

In the decorating of walls and ceilings in homes, offices and buildings, surfaces are often stippled to improve the appearance and to remove the brush marks from freshly painted surfaces. Roller types of stipplers have been used for stippling large areas of the walls and ceilings but as a result of their construction it has been practically impossible for these devices to work close to corners and molding strips. Upon completion of the roller stippling operation there was left a band of unstippled surfacing of from one half to three quarter inches wide in the corners and adjacent to molding strips. Either these bordering areas were left unstippled or the workman had to use a brush and tediously stipple these areas in.

An important object of this invention is to provide a stippling device of novel construction which with one stroke will stipple bordering areas in the corners and along molding strips and other projecting portions of the walls and ceilings. Another important object of the invention is to provide a device of this character having a freely rotatable head of novel formation which enables the head to enter confined spaces such as the wall corners or along molding strips of a wall and quickly impart the desired stippling effect without applying paint to any other surface portion than that intended. A further important object of the invention is to provide a novel device of this character which is formed of inexpensive parts easy to assemble for use.

In carrying out the invention the rotatable head of the device is provided with a novel conical formation and so mounted with respect to a handle that the device may be held so that outer wider diameter of the head may enter a corner between two angularly related surfaces and upon movement or stroke in one direction will stipple the area in the corner. In one form of the invention illustrated herein, the head is provided with an improved detachable covering which is so constructed that it may be slipped on the handle and automatically retained in position and which when worn may be conveniently replaced by another covering. In another form of the invention, the rotatable conical shaped head may be formed of yielding material and provided with novel projections which may be shaped to produce by suction the desired stippling effect. In a third modification of the invention the head of the device may be composed of two freely rotatable conical shaped members adapted to simul-

2

taneously stipple the bordering areas of two abutting angularly related surfaces in one stroke of the device.

Various other objects, advantages and meritorious features will become more fully apparent from the following specification, appended claims and accompanying drawings wherein:

Fig. 1 is a perspective view of the device of this invention illustrating the manner in which it operates in a corner formed by two abutting surfaces,

Fig. 2 is an end view of the device illustrating the manner of operating the device in a corner similar to that of Fig. 1,

Fig. 3 is an exploded view showing the parts of the device in the order of their assembly,

Fig. 4 is an assembled view of the device of Fig. 3 showing the head in vertical cross section,

Fig. 5 is a vertical cross section through the operating head of a modification of the device employing two juxtaposed freely rotatable conical members,

Fig. 6 is a vertical sectional view through a modified form of operating head having the covering material permanently secured thereto,

Fig. 7 is a vertical sectional view through a modified form of operating head composed of resilient material,

Fig. 8 is an enlarged detail view of a portion of the conical surface of the head of Fig. 7 taken along line 8—8 thereof, and

Fig. 9 is a sectional view taken along line 9—9 of Fig. 8.

In the embodiments of the invention illustrated in the drawing a desirable form is illustrated in Figs. 1 to 4 inclusive and includes a handle 10 having a blade member of metal 12 or like material projecting from one end thereof.

Rotatably secured to the outer end of the blade 12 is a stippling head of generally conical shape. The head comprises a base portion 14 of truncated formation having a back flat face 16 and a conical side wall 18 which extends at an acute angle of approximately 45° to the back face. The base 14 of the head is provided with an outer covering in the form of a hood 20 which forms a separate part of the assembly as indicated in Fig. 3. This covering may be composed of any suitable material for providing a stippling effect.

One desirable type of material is woven cloth, pile fabric, or carpeting having spaced circular strands 22 of resilient material such as rubber or the like incorporated therein. These strands yieldingly collapse the hood upon the base portion 14 when fitted thereover.

The head of the device is constructed for quick

assembly on the handle and for free rotation relative thereto. As shown in Fig. 3 the base 14 is provided with a bore 24 of reduced diameter which opens out on the base or back face 16 thereof and a wider bore 26 which opens out on the apex of the base. The two align with one another to form a passage entirely through the base member 14 from the apex end to the back face. Received through the passage formed by the two aligning bores 24 and 26 is an arbor or rivet 28 having a reduced end section 30 which is adapted to enter the hole 32 formed in the outer end of the supporting blade 12. The end of the rivet opposite to the reduced end section 30 is provided with a head 32 which is adapted to bear against the shoulder formed by the two bores 24 and 26. Received over the rivet member is a sleeve or ferrule 34 having a flange 36 which is adapted to abut the rear face 16 of the base portion 14 of the head. Between the base 14 and the blade 12 is a spacer member 38 which is provided with a hole 40 for receiving the reduced end section 30 of the rivet member.

Fig. 4 illustrates the assembly of the parts and as shown therein the spacer member 38 is disposed between the back face 16 of the base and the apertured end of the blade 12. The ferrule 34 is fitted tightly within the reduced bore 24 so that the base member is jointly rotatable therewith. The ferrule is freely rotatable upon the larger portion of the rivet member 28. The outer end of the reduced section 30 of the rivet member following its introduction into the hole 32 of the blade is peened over as indicated at 42 to secure the head to the blade 12. The covering material 29 is shown in Fig. 4 in assembled relation upon the blade 14. The covering extends over the opening formed by the larger bore 26 as shown in Fig. 4. The outer margin or edge 43 of the covering is lapped over the inner face 16 and by virtue of the resilient strands provided in the covering it is retained in position upon the base 14.

Figs. 1 and 2 illustrate the operation of the device in a corner formed by two angularly related abutting surfaces. One surface 44 has just been freshly painted. The other surface 46 may be a freshly painted surface of an adjacent wall or the edge of a molding strip projecting from the surface of the wall. Heretofore when roller stippling devices have been used there has been left an unstippled area or band indicated at 48 along the length of the corner formed by the two abutting surfaces. The handle of the device is grasped by the hands of the operator and the conical shaped head is introduced into the corner in the manner illustrated in Fig. 2 so that the back face 16 thereof extends at an acute angle to the two abutting surfaces and intersects the corner formed thereby. This brings the wider diameter of the head into the corner formed by the two abutting surfaces and the covering material of the conical side wall 18 against the unstippled band or border 48 along the corner. One stroke of the device such as in the direction of the arrow in Fig. 1 will impart the desired stippling effect to the border 48. During the movement of the device the conical head will rotate freely. It is to be noted that at the acute angle at which the device operates the folded or lapped over portions of the covering material 29 does not engage the surface 46 during the operation.

In Fig. 5 there is illustrated a modification of the invention wherein the head is composed of

two conical shaped members mounted for independent rotation about a common shaft. Such a device is adapted to be used for simultaneously stippling the bordering areas of two wall surfaces forming a corner of approximately 90°. Referring to Fig. 5 the handle portion 10 carries the supporting blade member 12 as previously described. Extending transversely through the outer end portion of the blade 12 is a member or arbor 50 which may be a headed bolt threaded for receiving a nut 52. The two conical members are indicated at 54—54 and correspond in shape and formation to one another and to the operating head previously described. Each conical member is bored out similarly to the head of the previous modification and a ferrule 56 is fitted into the reduced portion of the bore in the manner previously described. The ferrule 56 of each head 54 is of wider diameter than the bolt member 50 so that the conical members 54—54 have a slight angular play with respect thereto and may be inclined toward one another in the manner shown in Fig. 5. Encircling the bolt 50 on opposite sides of the blade 12 are two spacer members 58—58.

Normally the two heads of the device of Fig. 5 assume the position shown in dotted outline therein. However, when the head is introduced into a corner formed by the two abutting surfaces 30 and pressed lightly therein the two heads 54—54 will wedge in the corner and assume the angle with respect to one another as shown in full lines. Thereafter the device may be stroked in one direction or the other along the corner to impart the desired stippling effect to the bordering areas of the two abutting surfaces. The two heads 54—54 are so constructed that when they assume their angular relationship shown in Fig. 5 the substantially abutting edge portions thereof assume an angle of approximately 90°. As in the previously described embodiment of the invention the two heads 54—54 may each be provided with a covering material 60 which will impart the desired stippling effect.

In Fig. 6 there is illustrated a slightly different type of conical head in which the covering material is permanently secured thereto. As shown the conical head 62 is provided with a covering material 63 of carpeting or the like which is secured by a layer of glue 64 or other suitable adhesive material to the conical surfaces of the head. The head may be mounted on a bolt 65 which is freely rotatable in the apertured end of the supporting blade 12 and secured thereto by a nut 66.

In Fig. 7 the conical head is shown composed entirely of yieldable or resilient material. A body 68 of rubber or like material which will withstand deterioration in the presence of paint is shaped into the conical formation of the heads 14, 54 and 62 previously described. This body of resilient material is provided with axial bores 70 and 72 which correspond in size and function to the bores 24 and 26 previously described. An important feature of the type of head illustrated in Figs. 7 to 9 is the character of the surface which imparts the stipple to a freshly painted surface. Referring particularly to Figs. 8 and 9 the conical side wall of the rubber body is provided with a plurality of closely arranged projections 74 which are formed on the same material as the body 68 and are integrally joined thereto. Each projection 74 is indented or formed with a concave recess 76 as shown in Fig. 9 on the outer end thereof. As these projections

press into the freshly painted surface the concave ends thereof are slightly compressed and as a result create a suction which as the projections leave the painted walls form the stipple that is desired.

While there has been described, what is at present considered to be, certain preferred embodiments of the invention, it will be obvious to those skilled in the art that various changes and modifications may be made therein without departing from the invention and it is, therefore, desired in the appended claims to cover all such changes and modifications as fall within the true spirit and scope of the invention.

What I claim is:

1. A device for stippling corner areas of wall surfaces comprising, in combination, an elongated handle, a pair of conical shaped rollers, means for mounting said rollers on opposite sides of one end of the handle and providing rotation thereof about axes substantially in alignment with one another and substantially perpendicular to the plane of the handle, and means on the conical side wall of each roller for imparting a stippling effect to the surface upon which the rollers are rolled.

2. A device for stippling corner areas of wall surfaces comprising, in combination, an elongated handle, a pair of conical shaped rollers, means for connecting said rollers to opposite sides of one end of the handle with the base ends

thereof located adjacent to the end of the handle, said means journaling each roller for rotation about its respective axis and providing an angular movement of the rollers relative to the handle so that the base ends of the rollers may be brought into substantial engagement beyond the end of the handle to which they are connected whereby both rollers may simultaneously engage the adjacent marginal areas of two angularly extending surfaces of a corner of a wall, and means on the conical side wall of each roller for imparting a stippling effect to the surface upon which the roller is rolled.
